~~Design No. 252~~

Gardner Chilson

Design for Patent Registration
Patented 20 March 1887.Dec. 352

Gardner Chilson of Boston Mass.
Letters Patent No. 352. Dated March 4, 1851.

The Schedule referred to in these Letters Patent and making part of the same;
To all persons to whom

these Presents shall come:

Be it known, that I, Gardner Chilson, of Boston, in the County of Suffolk and State of Massachusetts, have invented, or produced, a new and original design for a register for furnaces, and I do hereby declare that the following description and accompanying drawing, form a full and exact specification and representation of the same.

My new design is in the form of a circle as shown in the accompanying drawing, which is a plan or top view of the same. The centre of the register is occupied by the ring a, a, enclosing the eight leaved star b, b, with a small circle c in its centre. From the edge of this ring a, a, curved and notched branches, or bars, radiate to the larger ring d, d, d, forming the irregular openings e, e, f, f, & c. and the heart shaped openings g, g, &c. near the edge of said ring d, d, d. Midway between this ring d, d, d, and the outer ring h, h, h, is another ring i, i, i. The spaces between these several rings d, d, d, h, h, h, and i, i, i, are ornamented by curved branches, or bars, forming the hyperbola shaped openings k, k, k, &c. The whole forming an ornamental lattice or open work for the passage of the heat.

Having thus described my new design, I shall state my claim as follows:

What I claim as my production, and desire to have secured to me by Letters Patent, is the new design, herein above described, for a register, in the form of a circle, having within and near to its outer ring, two concentric rings, the space between each of said rings being ornamented with curved lattice work, forming hyperbola shaped openings, and a ring in its centre, enclosing an eight leaved star with a small circle in its centre, and curved and notched branches radiating from the said ring, to the smaller of the outer rings, forming irregular and heart shaped openings, all as herein above described and shown in the drawing.
